UNITED STATES PATENT OFFICE.

KARL FROHNHÄUSER, OF DORTMUND, GERMANY.

APPARATUS FOR CONVEYING GRANULATED MATERIALS.

SPECIFICATION forming part of Letters Patent No. 675,882, dated June 4, 1901.

Application filed March 15, 1901. Serial No. 51,376. (No model.)

To all whom it may concern:

Be it known that I, KARL FROHNHÄUSER, engineer, a subject of the Emperor of Germany, residing at Dortmund, Germany, have 5 invented certain new and useful Improvements in Apparatus for Conveying Granulated Materials; and I do hereby declare the following to be a full, clear, and exact description of the invention, such as will enable others skilled in the art to which it 10 pertains to make and use the same.

The present invention relates to an improved apparatus for conveying granulated materials, such as coal, sand, and the like.

15 The invention consists in the combination of known mechanical means employed for this purpose—such as, for instance, endless chains and such like—with a stream of water moving in the direction in which the material is being transported.

20 Of the accompanying drawings, Figure 1 is a sectional side elevation of my improved apparatus; Fig. 2, a plan view of the arrangement shown in Fig. 1; Fig. 3, a plan view of 25 a modification. Fig. 4 is a longitudinal sectional view, on an enlarged scale, of the conveyer-trough and parts therein. Fig. 5 is a transverse sectional view of the parts shown in Fig. 4.

30 The same letters of reference designate the same parts in all the figures.

b is a long trough or gutter open at the top and arranged to connect the two points between which the conveyance of the material 35 is to take place.

e is a water-pipe connecting the ends of the trough *b* and provided with a cock *d*.

f is an endless chain provided with paddles and carried around a suitable number of pulleys *i*, by the rotation of which it can be 40 kept in motion.

a is a hopper by which the granulated material can be fed into the apparatus, and *c* is a second hopper, by which the material is 45 charged after passing along the trough *b*.

In the modification shown in Fig. 3 the 50 number of troughs *b* is multiplied and they are all connected at the discharge end by branches *h*, which lead the water into a common receiver *g*, from which it is carried back through pipe *e* to the receiving ends of the troughs.

The operation of the herein-described apparatus is as follows: The trough *b* is kept full of water by any convenient means of supply. The material—for instance, coal—is continuously or periodically fed into the hopper *a*. Here the chain *f*, being constantly kept in motion, seizes the material and with the aid of the water easily distributes it and spreads it out along the trough *b* and carries it onward toward the discharge-hopper *c*. The effect of the water is to considerably reduce the weight of the material that is being conveyed and at the same time as the water, 60 as well as the material, is kept in constant motion by the chain it washes along the latter, and thereby aids the action of the paddles in conveying the material.

In the modification of my apparatus shown 70 in Fig. 3 no chain is supposed to be provided in the branches *h*, because the amount of water passing through these parts in the unit of time will be greater than that passing along the branches *b*, and therefore the wash of the 75 water alone will in these parts be sufficient to convey the material.

I am aware that the method of washing granulated materials along a trough or canal by means of a stream of water is not new, 80 and I am also aware that mechanical means—such as endless chains, endless bands, and the like—are also usually employed for conveying materials of this kind from one place to another; but, as I have particularly described in the foregoing specification, 85

What I claim as my invention is—

1. In a conveyer for granulated material, the combination of a trough or conduit on the floor of which the material is supported while 90 being transported, a body of liquid in said conduit, and a propelling means arranged to move longitudinally of the conduit and engage said material, the said liquid reducing the weight and friction of the material and 95 assisting in conveying the same.

2. In a conveyer for granulated material, the combination of a trough or conduit on the floor of which the material is supported while being transported, a body of liquid in 100 said trough into which the material to be conveyed is delivered, and means for moving said material and liquid longitudinally of the trough or conduit, for the purpose set forth.

3. In a conveyer for granulated material, the combination of a trough or conduit on the floor of which the material is supported while being transported, a body of liquid within said trough and into which the material to be moved is delivered, an endless power-transmitter extending for a portion of its length through said liquid and adapted to move material therein longitudinally of the conduit and cause a movement of the liquid in the same direction, for the purpose set forth.

4. In a conveyer for granulated material, the combination of a trough or conduit on the floor of which the material is supported while being transported, a mechanical conveyer operating in said conduit to move said granulated material longitudinally thereof, and means for continuously supplying water to said trough or conduit, for the purpose set forth.

5. In a conveyer for granulated material, the combination of a trough or conduit, a body of water in said conduit, a mechanical con-

veyer operating in said conduit to move the granulated material and water therein longitudinally thereof, and means for repeatedly returning the water to the trough or conduit.

6. An apparatus for conveying granulated materials consisting of a trough, an endless chain provided with suitable paddles, means for keeping said chain in motion along the bottom of said trough, a sufficient supply of water in said trough and moving under the impulse of the paddles in the direction of the motion of the material, and a conduit connecting the ends of the trough for conducting water in a direction opposite to that in which the paddles move through the trough, substantially as and for the purposes set forth.

In witness whereof I have hereunto set my hand in presence of two witnesses.

KARL FROHNHÄUSER.
